ABSTRACT: A ring and traveler assembly for use in a spinning or twisting frame including spaced ring members that define a slot therebetween, a traveler having a projecting portion extending through the slot and being mounted on flanges of the ring members, one ring member being movable relative to the other to increase the size of the slot therebetween, thereby enabling the traveler to be easily mounted between the ring members.

FIG. 1

FIG. 2

FIG. 3

INVENTOR
 DERREL V. MYERS
 BY *Salter & Michaelson*
 ATTORNEYS

RING AND TRAVELER ASSEMBLY

BACKGROUND OF THE INVENTION

The present invention relates to a ring and traveler assembly and has particular application in a spinning or twisting frame, the traveler member that forms a part of the assembly defining a guide for a yarn that is being removed from a bobbin for processing.

The ring traveler commonly in use heretofore was usually constructed in the form of a bail having inturned projecting portions that engaged beneath the edges of a flange on the upper edge of a spinner ring. In this form of ring traveler, the thread being removed from a bobbin, passed under the bail, and supported the bail as the bail followed the spinner ring support in circular relation and as the thread was removed from the bobbin. Such constructions have not been found to be very satisfactory since the thread continually pressed against the inturned ends of the bail thereby creating a force and causing friction and wear that eventually resulted in resistance of movement of the ring traveler on the spinner ring. In such prior known constructions, the bail had a tendency to drop when not in use so that when the spinner ring was started up, the ring traveler was snapped upwardly into frictional engagement with the spinner ring that either caused the bail to break or resulted in overstraining thereof. The bail constructions as known heretofore also had a tendency to break when being forced over the spinner ring upon mounting of the bail in its position of use. Further, because of the need for forcing the inturned ends of the bail over the spinner ring, the configuration of the bail was sometimes changed to the extent that proper movement of the bail on its track was prevented.

Some efforts have been made heretofore to vary the constructions of these ring travelers, but normally they have consisted only of a means for securing to the traveler some device for receiving the yarn as it was removed from the bobbin. Thus in the prior known traveler constructions, they were still snapped in place over the ring carrier by forcing the inturned ends thereof over the flange of the spinner ring, which eventually resulted in misalignment or breaking of the traveler.

SUMMARY OF THE INVENTION

The ring and traveler assembly as embodied in the present invention has application in a spinning or twisting frame and includes a first ring member from which a second ring member is spaced in coaxial relation with respect thereto. The spacing between the ring members defines an annular slot and a traveler member having a projecting portion received in the slot is mounted on the ring members and is slidable relative thereto, the projection portion being freely movable within the annular slot. The ring members are secured by a fastening member in their spaced apart position, but may be urged apart against the action of a spring when the projecting portion of the traveler member is inserted within the annular slot. The spacing between the ring members may also be varied by means of a spacer member located therebetween so that a variety of different size traveler members may be incorporated in the assembly.

Accordingly, it is an object of the present invention to provide a ring and traveler assembly for use in a spinning and twisting frame that includes spaced ring members that receive a traveler member therebetween.

Another object of the invention is to provide a traveler member for use in a ring and traveler assembly that has a projecting portion that is received in a slot that is defined by spaced ring members, the traveler member being freely movable with respect to the ring members as it is guided by the confines of the slot.

Still another object is to provide a ring and traveler assembly having spaced ring members on which a traveler member is mounted and including means for varying the spacing between the ring members so as to accommodate various size traveler members.

Other objects, features and advantages of the invention will become apparent as the description thereof proceeds when considered in connection with the accompanying illustrative drawings.

DESCRIPTION OF THE DRAWING

FIG. 1 is a bottom perspective view of the ring and traveler assembly embodied in the present invention;

FIG. 2 is a vertical sectional view taken along line 2-2 in FIG. 1; and

FIG. 3 is an enlarged fragmentary sectional view showing the traveler member as mounted on the ring members illustrated in FIGS. 1 and 2.

DESCRIPTION OF THE INVENTION

Referring now to the drawing, the ring and traveler assembly embodied in the present invention is generally indicated at 10 and as shown has particular application in a spinning or twisting frame a portion of which is indicated at 12. It is understood that the ring and traveler assembly 10 will encircle a bobbin or the like from which yarn or thread is removed for processing, the ring and traveler assembly 10 providing for uniform tension of the thread as it is removed from the bobbin and further preventing kinking or unnatural twisting of the thread as it is removed from the bobbin.

In contradistinction to the ring and traveler assemblies known heretofore, the present invention includes a first or upper ring member generally indicated at 14 from which is spaced a second or lower ring member generally indicated at 16. Although the axes of the upper and lower ring members 14 and 16 are illustrated as being vertical, it is contemplated that the axes of the ring members may be disposed in a horizontal direction or inclined with respect to the horizontal, depending upon the requirements of the spinning or twisting frame on which the ring members are mounted. As illustrated in FIG. 2, the upper and lower ring members 14 and 16 are located in coaxial relation, the lower ring member including a rear extension 18 that is adapted to be attached to the frame 12 by means of bolts 20. As will be described, the upper ring member 14 is mounted for pivotal movement on the lower ring member 16, the pivotal movement of the upper ring member enabling the spacing between the ring members to be temporarily increased for inserting a traveler member in the assembly as will also be described hereinafter.

The upper ring member 14 is defined by an annular ring portion 22 having an upper flange 24 and a lower flange 26 integrally jointed thereto. Extending outwardly of the ring portion 22 is an annular reduced section 27 to which an extension 28 is joined, a hole 30 being formed in the extension 28. Joined to the reduced section 27 diametrically opposite to the extension 28 is an extension 32 to which a hinge element 34 is connected by means of screw fasteners 36. The lower ring member 16 is defined by a ring portion 38 to which flanges 40 and 42 are integrally joined. An annular reduced section 43 is joined to the ring portion 38 and underlies the annular reduced section 27 to define an annular channel 44. An extension 45 is joined to the section 43 and underlies the extension 28, an opening 46 being formed in the extension 45 in aligned relation with respect to the opening 30. As will be described, a bolt 48 projects through the openings 30 and 46 and receives a wing nut 50 on the threaded lower end thereof. A spring 52 is located in surrounding relation around the bolt 48 and is disposed between the lower end of the extension 45 and the wing nut 50. The extension 18 of the lower ring member 16 is joined integrally to the ring portion 38 through the reduced section 43 and a hinge element 54 is connected to the extension 18 by screw fasteners 56. A pin 58 integrally interconnects the hinge elements 34 and 54, thereby pivotally mounting the upper ring member 14 with respect to lower ring member 16.

The upper ring member 14 is spaced from the lower ring member 16 so that the annular flanges 26 and 40 are spaced

from each other to define a slot 60 therebetween. The slot 60 may be varied in vertical dimension in order to accommodate various size traveler members, to be described, and in order to locate the ring members 14 and 16 in their spaced apart relation a spacer member 62 is provided and is positioned between the extensions 28 and 45, as illustrated in FIG. 2. As further shown in FIG. 2, the spacer member 62 as located between the extensions 28 and 45 of the ring members 14 and 16 respectively, receives the bolt 48 therein and thus is retained in the position as illustrated for locating the ring members 14 and 16 in their spaced apart relation so as to define the spacing of the slot 60. It is understood that the spacing of the slot 60 may be varied by changing the spacer member 62 for a different spacer member of either greater or smaller thickness.

In order to receive a yarn indicated at 64 in FIG. 3 from a bobbin, and for guiding the yarn to a spinning or twisting frame for further processing, a traveler member generally indicated at 66 is provided and is adapted to be mounted for sliding movement around the ring members 14 and 16. As illustrated in FIG. 3, the traveler member 66 is defined by an elongated portion 68 that terminates at the upper end in a hook portion 70 and to which a projecting portion 72 is joined adjacent the lower end thereof to form a C-configuration therewith. The projecting portion is formed with flanges 74 and 76 that are adapted to be captured behind the flanges 26 and 40 of the ring members 14 and 16 and within the annular channel 44. The traveler member 66 may be formed of any desirable material such as ceramic, glass, nylon, hard rubber, bakelite, boron or even of other materials of a brittle nature heretofore not suitable or possible to use in the prior known traveler members.

In mounting of the traveler member 66 on the ring and traveler assembly, the upper ring member 14 is lifted with respect to the lower ring member 16 and against the action of the spring 52. This movement enlarges the slot 60 and enables the projecting portion 72 of the traveler member 66 to be received between the flanges 26 and 40 of the upper and lower ring members. The hooked portion 70 is placed over the upper flange 24 of the ring member 14 and when the upper ring member 14 is released, the spring member 52 returns the ring member 14 to its normal position to lock the flanges 74 and 76 of the projecting portion 72 behind the flanges 26 and 40 of the upper and lower ring members. With the hooked portion 70 locked on the upper flange 24 of the upper ring member 14 the traveler member 66 is now mounted in place for sliding movement on the upper and lower ring members 14 and 16. It is seen that the flange 24 of the upper ring member 14 and the flange 40 of the lower ring member 16 define tracks for carrying the traveler member 66 as it slides around the ring members in the operation thereof. As again seen in FIG. 3, the elongated portion 68 of the traveler member adjacent to the hook portion 70 is formed with a concave inner area 78 that receives the yarn 64 therein. This provides sufficient space for the yarn to pass therethrough as the traveler member 66 moves around the ring members 14 and 16.

It is seen that the tandem ring member assembly and traveler are adaptable for using either a fine denier or heavy denier yarn due to that fact that the spacing between ring members 14 and 16 may be varied to receive relatively light and small dimensioned travelers for fine denier and relatively heavy and bulky travelers for heavy denier yarn. This change in spacing as heretofore described is accomplished by changing the spacer member 62 between the ring members so as to change the dimension of the slot 60 in order to properly receive the particular traveler being used. Because of the manner of mounting of the traveler member 66 on the ring members, a heretofore known problem of the traveler member flying off its spinner ring under centrifugal force is eliminated; and it is also seen that by providing for lifting of the ring member 14 with respect to the ring member 16 through use of the spring 52, breaking or snapping of the traveler members when mounting in place is avoided. For this reason various kinds of materials may be employed in the construction of the traveler member, and it is contemplated that

relatively inexpensive materials of a brittle nature may be utilized in the manufacture of the traveler members. Because of the free movement of the traveler members with respect to the ring members as mounted therebetween, higher speeds of the traveler member may be obtained, which results in higher operating efficiency of the equipment with lower costs resulting therefrom.

I claim:

1. In a ring and traveler assembly for use in a spinning or twisting frame, a first ring member, a second ring member separable from and spaced with respect to said first ring member and located in coaxial relation therewith, the spacing between said ring members defining an annular slot, a traveler member having a projecting portion that is received in said slot in free sliding relation, wherein said traveler member is fully movable with respect to said ring members, and means for securing said ring members in their spaced apart position and means cooperating with said securing means for varying the spacing between said ring members, thereby varying the dimension of said slot, each of said ring members having an annular flange formed thereon, said flanges being spaced from each other to define said slot, the portion of said traveler member that projects into said slot having a flange formed thereon that has a dimension greater than that of the slot, wherein said flange on said traveler member prevents withdrawal of said traveler member from between said ring members during movement thereof, said traveler member further including a hook portion that is received over the flange of one of said ring members and cooperates with the flange on said traveler member to define gripping portions for retaining said traveler member in sliding position on the flange of said one ring member.
2. In a ring and traveler assembly for use in a spinning or twisting frame, a first ring member, a second ring member separable from and spaced with respect to said first ring member and located in coaxial relation therewith, the spacing between said ring members defining an annular slot, a traveler member having a projecting portion that is received in said slot in free sliding relation, wherein said traveler member is fully movable with respect to said ring members, and means for securing said ring members in their spaced apart position and means cooperating with said securing means for varying the spacing between said ring members, thereby varying the dimension of said slot, said securing means including a fastener that extends through extensions formed on said ring members, and resilient means located on said fastener and providing for biased separation of said ring members for enlarging said slot wherein the projecting portion of said traveler member is more easily receivable in said slot for mounting said traveler member therein.
3. In a ring and traveler assembly as set forth in claim 2, one of said ring members being pivotal with respect to the other, and said fastener being located diametrically opposite to the pivot axis of said ring members for normally securing said ring members against movement.
4. In a ring and traveler assembly as set forth in claim 2, said means for varying the spacing between said ring members including a spacer element that is located between said extensions and that receives said fastener therethrough, said spacer element being interchangeable with a spacer element of different thickness to vary the spacing between said ring members.
5. In a traveler member for use in a ring and traveler assembly, an elongated vertically disposed body, a first projecting portion extending inwardly from the top end of said body and having a depending hook portion at its extremity, a second projecting portion extending inwardly with respect thereto, said first projecting portion and the upper side of said second projecting portion cooperating to define a C-shaped configuration adapted to receive a first ring member therebetween, the lower side of said second projecting portion and the bottom portion of said body cooperating to define an inverted U-shaped configuration adapted to receive the upper end of a second ring member mounted in spaced relation to the first ring member.
